UNITED STATES PATENT OFFICE.

HOLMES B. GRONINGER, OF PORT ROYAL, PENNSYLVANIA.

WELDING FURNACE.

Application filed May 1, 1926. Serial No. 105,938.

My invention relates to the structure of furnaces for heating bent skelp preparatory to welding the skelp into pipe. Such structures include a substantially horizontal 5 hearth upon which the bent skelp rests and over which it is rolled as it is being heated to welding temperature. Along the hearth extends a gutter, and into this gutter the heated length of bent skelp is ultimately 10 rolled, and from this gutter the heated length of bent skelp is ultimately pushed to enter the pass of the welding machine. The gutter necessarily endures heavy wear. Common practice is to form it as a groove 15 in a block of solid refractory material and to maintain it during operation partially filled with loose sand. As operation progresses the sand is dragged away, and at frequent intervals operation has to be arrested, 20 while the supply of sand is replenished. The incidental loss in time and labor cost is appreciable.

In the accompanying drawings Fig. I is a view in vertical and transverse section of 25 an annealing furnace in which my invention is embodied. Fig. II is a view in vertical and longitudinal section. The plane of section of Fig. I is indicated at I—I, Fig. II, and the plane of section of Fig. II is indicated at II—II, Fig. I. Fig. III being a fragmentary view in horizontal section near the base of the structure, shows in plan the driving mechanism of that feature in which my invention centers. Fig. IV is a fragmentary view in vertical and transverse section, 30 and shows in elevation a certain pawl and ratchet attachment to the driving mechanism. Figs. III and IV are drawn to some-what larger scale than the other figures. Fig. V is a fragmentary view, corresponding 35 in the main to Fig. II, and illustrating a certain modification in detail.

Referring, first, to Fig. I, the hearth of the heating furnace there shown is indicated 40 at 1 and in this hearth is formed the gutter 2. The hearth, as ordinarily is the practice, is formed of hard packed sand, and the gutter is formed in the body 3 of solid refractory material. I make this body 3 vertically movable; I am no longer dependent 45 in operation upon the presence of a given quantity, or indeed of any quantity of sand within the gutter, but as the gutter wears away I make compensation for wear by the

elevation of the body 3, and this adjustment 55 of the body 3 becomes possible without interruption of operation. Thus I gain continuity of operation, which is an end of great practical value.

As best shown in Fig. II the body 3 of refractory material will practically be made up of a plurality of blocks suitably supported, as upon an underlying beam 4. Particular means for effecting elevation—and the showing here is exemplary, merely— 60 are shown in Figs. I—IV. The beam 4 is carried upon vertically standing posts 5. These posts are provided with teeth, and the teeth are engaged by cogs 6 borne upon shafts 7. The shafts may be turned by suitable means, 65 as by a hand crank 8, and retrograde turning may be prevented by the pawl and ratchet device particularly shown in Fig. IV. An attendant may from time to time 70 turn crank arm 8 and raise block 3 and thus 75 make compensation for wear, and this without any interruption at all of the continuity of operation.

A plurality of posts 5 will ordinarily be provided in any given furnace. In Fig. II 80 two posts are shown, and the organization is such that these two posts are elevated in unison. In Fig. II, furthermore, the posts are shown to be bolted to beam 4. In Fig. V the engagement of posts 51 with beam 4 is 85 shown to be in the form of a ball and socket joint. It will be apparent that if engagement be in this form the posts may be elevated each independently of the other, and accordingly the rate of elevation at one end may 90 be greater than at the other, to adapt the device to conditions of unequal wear. The particular means shown in Figs. I—IV for elevating the posts is exemplary, merely, and, given the assembly of beam 4 with posts 95 5 (or 51) the engineer has the knowledge of the art available to him for effecting elevation of the posts, either in unison or independently, as conditions of service may dictate.

I claim as my invention:

1. In a heating furnace including a hearth with a guttered margin, the guttered margin being vertically adjustable with respect to the remainder of the hearth.
2. In a heating furnace a horizontally extending hearth, a body of solid refractory material forming part of the hearth, such

body being grooved upon its upper surface and such body being adjustable vertically in its position as a component member of the hearth.

5 3. In a heating furnace a horizontally extending hearth, a vertically movable body of solid refractory material grooved upon

its upper surface forming part of the hearth, and means for adjusting said body of refractory material in its position.

10 In testimony whereof I have hereunto set my hand.

HOLMES B. GRONINGER.
